[57] ABSTRACT

[22] Filed: **Oct. 25, 1972**

A mounting assembly for a mining tool adapted to fit in a bit block consisting of a hub assembly having an axial opening therethrough of a size to journal a mining cutter bit. The bit block has a larger opening adapted to accept the hub assembly and permit rotation of the hub assembly in the bit block. The hub assembly extends over the bit block so that a seal can be mounted between the bit block and the hub assembly. A peripheral groove is formed in the hub assembly so that a screw can lock the hub assembly into the bit block.

ROTATING HUB ASSEMBLY FOR A MINING CUTTER BIT

PRIOR ART

The closest patent relating to the hub assembly is the 5 patent to T. J. Kniff, U.S. Pat. No. 3,499,685. This patent discloses a bit block having a sleeve mounted into the bit block and an axial opening in the sleeve adapted to hold and retain a cutter bit. The sleeve and the cutter bit are free to rotate. The principal purpose of the Kniff patent is to permit replacement of the shoulder support for the bit block. A secondary purpose is to permit rotation of the sleeve assembly as well as the cutter bit. There is no provision, however, in the aforementioned device for preventing the entrance of coal dust and other materials between the bearing surfaces causing binding of the bit and loss of rotation. Since bits are continuously washed with water, it is fairly easy to form a fine water-coal slurry which will enter most exposed bearing surfaces.

Various other means have been tried to insure bit rotation. Ridges or flutes have been made on the sides of the conical bits; and projections of various types have been welded or attached to the base of the cone. These measures increase the bit life; however, the bit life could be increased further if the rotation of the bit was insured.

BRIEF DESCRIPTION OF THE FIGURES

FIG. 1 is a cross-sectional view of the hub assembly 30 with the cutter bit in full view; and

FIG. 2 is a top view of FIG. 1 having a partial section through lines 2—2 of FIG. 1.

Referring to both FIGS. 1 and 2, a bit block 10 is attached to a continuous mining machine belt 11 by 35 means of a weld or other suitable attaching means 12. The bit block 10 has an axial opening 13 for receiving a rotatably journaling hub assembly generally referred to as 14. Hub assembly 14 essentially comprises a cylinder portion 15, a second cylinder portion 16 having a larger diameter than portion 15, a downwardly extending circumferential lip 17, and an axial opening 18 adapted to receive cutter bit 19. A plurality of impact arms 20 is attached normal to the surface of cylindrical portion 16. Axial opening 18 has a circumferential groove 21 adapted to receive a locking ring 22 having a plurality of dimples 23 which snap into circumferential groove 21 and retain the cutter bit in axial opening 18. The cutter bit is of the usual type having a shank 30, a removal groove 31, a conical tip 32, and a hardened tungsten carbide insert tip 33. Such bits are readily available on the market and, as such, will not be further discussed. Cylindrical portion 15 has a circumferential groove 40 which mates with a threaded opening 41 having a bolt 42 therein. The tip 43 of bolt 42 fits into groove 40 and retains hub assembly 14 in axial opening 13. The seal assembly comprises a projection 50 on the bit block 10 which has a recess 51. Seal 52 fits into recess 51 and extends to the inside of the circumferential lip 17. Since the seal is fairly well restrained from movement, no means need be provided for anchoring the seal in recess 51. The space between bit block and cylindrical portion 15 may be lubricated by any suitable lubricant, such as grease, oil, graphite, or the like. In some instances it may be preferable to leave any form of lubricant out of the space, since, in spite of the seal, some dust may get into the lubricant, causing the

hub assembly to bind to bit block 10 when the dust mixes with the lubricant.

Operation

Unlike the prior art, dust, dirt and water are prevented from entering the bearing surface between bit block 10 and cylindrical portion 15 by virtue of the seal 52. Any dirt or dust entering the passageway will be blocked effectively by the seal. The seal also provides for free rotation of the hub assembly. The cutter bit 19 is also free to rotate. If the hub assembly should bind, bolt 42 can be removed and the hub assembly lifted out and cleaned. The seal can also easily be replaced using the same procedure.

15 A second advantage is that, should the area around the shoulder of the cutter bit become damaged due to impacting of product, such as coal, the hub assembly can be removed; and a new one can be substituted without necessitating breaking the weld 12 and substituting an entire new bit block. The impacting arm 20 being formed on the cylindrical portion 16 provides a method of insuring rotation of the hub assembly. Since the impact arm 20 is mounted to the hub assembly, there is no need to provide additional impact arms on the cutter bit 19, thus reducing the cost of the cutter bit. Seal 52 may be made of any suitable seal material, such as rubber or one or more of the manufactured plastics.

20 A sealed hub assembly has been disclosed which will function in spite of the environmental contaminants in the region of the cutter bit. The seal assembly, furthermore, is easy to maintain.

25 It is obvious that modifications and changes can be made in the method of mounting the seal or seal materials and still be within the scope of the specification and appended claims.

30 What we claim is:

1. A mounting for a mining tool comprising:
a. a bit block;
b. a hub assembly having an axial opening there-
through of a size to journal a mining cutter bit;
c. means for rotatably journaling said hub assembly
in said bit block; and
d. seal means between said hub assembly and said bit
block,

35 whereby said hub assembly is free to rotate in said bit block, said seal means preventing the intrusion of dust particles on said bearing surface.

40 2. A mounting assembly as described in claim 1
wherein said hub assembly has a plurality of impact ex-
tensions formed normal to the surface of said hub as-
sembly.

45 3. A mounting assembly as described in claim 1
wherein said hub assembly contains a peripheral
groove and wherein said bit block includes a screw
means aligned with said peripheral groove for retaining
50 said hub assembly in said bit block, yet permitting said
hub assembly to rotate.

55 4. A hub assembly for a cutter bit comprising a bit
block having an axial opening therein; a hub assembly
60 having a cylindrical portion dimensioned to fit the axial
opening in said bit block, said cylindrical portion hav-
ing a length sufficient to extend from said axial open-
ing, said portion extending from said axial opening hav-
ing a circumferential lip, a circumferential seal; means
for mounting said circumferential seal between said bit
block and said circumferential lip; a peripheral groove
65 in said cylindrical portion dimensioned to fit said axial

opening in said bit block; retainer means mounted in said bit block and engaging said circumferential groove; and an axial opening in said hub assembly of a size to receive said cutter bit.

5. An assembly as described in claim 4 having a plurality of impact arms mounted normal to the surface of said hub assembly.
